UNITED STATES PATENT OFFICE

WILLIAM L. COOPER, OF KANKAKEE, ILLINOIS, ASSIGNOR TO SEARS, ROEBUCK AND CO., OF CHICAGO, ILLINOIS, A CORPORATION OF NEW YORK

COOKING STOVE

Application filed November 12, 1928. Serial No. 318,651.

The invention relates generally to improvements in cooking stoves and has particular reference to liquid fuel stoves of the type embodying a plurality of oil burners and operating mechanism therefor disposed beneath an open top.

An object of the invention is to provide a new and improved burner skirt for oil cook stoves, which is simple and inexpensive in 10 construction, enhances the appearance of the stove, and facilitates cleaning of the stove and the maintenance thereof in clean condition.

A more specific object of the invention resides in the provision, in a stove of this character, of a new and improved one piece burner skirt which serves as a complete permanent closure for the lower front portion of the burner space below the burners.

Other objects and advantages will become apparent from the following description and in the accompanying drawings, in which:

Figure 1 is an elevational view of the front of a cooking stove embodying the invention.

Fig. 2 is an enlarged fragmentary vertical section taken substantially on the line 2—2 of Fig. 1.

Fig. 3 is an enlarged fragmentary view in perspective showing certain details of construction of the burner skirt.

While the invention is susceptible of various modifications and alternative constructions, I have shown in the drawings and will herein describe in detail the preferred embodiment, but it is to be understood that I do not thereby intend to limit the invention to the specific form disclosed but intend to cover all modifications and alternative constructions falling within the spirit and scope 35 of the invention as expressed in the appended claims.

In illustrating the preferred embodiment of this invention, a commercially well-known type of fuel oil cooking stove has been shown. 45 Generally such a stove comprises a cooking top 5 in which the usual burner openings (not shown) are provided. A back 6 is secured upon the rear side of the top and downwardly extending side walls 7 and back 7^a secured 50 to the bottom of the stove top provide a

burner space in the form of an open front compartment immediately beneath the stove top. Legs 8 from each corner of the burner case support the stove from the floor. A shelf or tray 8^a may also be provided by securing a properly formed flat member to the legs 8, a short distance above the floor line. 55

The burner system, in this embodiment, is of the type generally known as a constant level fuel oil system, in which a plurality of burners 9 are individually movable vertically by suitable operating mechanism 10 (Fig. 2) to admit or prevent the flow of fuel oil from a supply tank 11. The form of operating mechanism disclosed herein is shown and more fully described in the copending application of Leon D. Fortier and myself covering improvements in liquid fuel stoves, Serial No. 210,513, filed August 4, 1927. 60

Manual actuation of the burners is by 70 means of an operating handle 12 for each burner. The burners 9 are suitably mounted within the burner space formed by the walls 7 and 7^a and are disposed in underlying relation to the cooking openings in the top 5. 75 Preferably a reinforcing member 13 (Fig. 2) which is herein shown in the form of a channel bar extending across the front of the burner case and rigidly secured to the side walls 7, lends rigidity to the stove assembly 80 and is arranged to support the burner skirt as will be hereinafter set forth.

It has been generally customary in prior constructions to provide a bottom wall in the form of a tray for the burner space located 85 a short distance beneath the operating mechanism for raising and lowering the burners. Moreover, former constructions of the burner skirt provided a flat plate extending across the open front of the burner space in front of the operating mechanism with the lower edge thereof spaced a short distance above the bottom wall of the burner space. In a stove embodying this construction it is 90 exceedingly difficult to clean the interior of the burner space and top tray of accumulations of grease and dirt due to the very narrow opening between the burner skirt and the tray, which forms the only means of in- 95 100

gress to the interior of the lower portion of burner space.

The present invention remedies this unsanitary condition by eliminating the bottom wall or tray, and, in its stead, providing a complete closure for the lower portion of the burner space in the nature of a combined vertical and forwardly extending horizontal partition.

10 In its preferred embodiment, the burner skirt 14 comprises an elongated plate of sufficient length to extend transversely across the open front face of the burner space and to fit snugly between the side walls 7. The 15 skirt is preferably formed of sheet metal and has an upper portion 15 of ample width to conceal the operating mechanism 10 for the burners. The top edge of the upper portion 15 may be turned rearwardly to form a 20 strengthening flange 16 and each side edge may also be turned rearwardly to form securing flanges 17 (Fig. 3) by which the skirt is secured to the side walls 7. An aperture 19 for each of the operating members 12 permits 25 the members to extend through and forwardly of the burner skirt. If desired, a portion of the face of the upper portion may be offset as at 20 to form a decorative panel.

The burner skirt also includes a lower portion 21, in the form of what may be termed a narrow shelf or sill, positioned to underlie the operating members 12 across the front of the stove. The shelf is constructed by turning or bending an integral part of the burner 35 skirt forwardly from the upper portion. The position of the lower portion 21 is substantially in the plane of the upper side of the reinforcing member 13 and near the forward edge thereof is bent downwardly, as at 22, 40 and then rearwardly, as at 23, to form an inwardly facing channel adapted to fit about and embrace the reinforcing member 13. Side flanges 24 may also be formed on the lower portion in the same manner and for the 45 same purpose as the flanges 17. Preferably the bend between the upper and lower portions of the burner skirt is on a suitably large radius to form a pleasing, smoothly rounded corner which may be easily cleaned.

50 In the assembled relation of the burner skirt in the stove it will be seen that the upper portion of the burner skirt is spaced inwardly of the burner space a substantial distance from the open front face of the case, 55 and that the channel formed on the front side of the lower portion fits about and conceals the reinforcing member 13. The front pair of legs 8 are secured in position on the corners of the case overlying and concealing the junction of the lower portion with the side walls 7 thereby enhancing the attractive appearance of the stove.

From the foregoing description, it will be apparent that a burner skirt has been provided which facilitates the cleaning of the stove.

Obviously, any dirt, which might be created in the operation of the stove, will fall and be caught and held upon the tray 8^a which, of course, may be easily kept clean. Furthermore since the burner skirt may be finished in any suitable manner and since the skirt entirely covers the lower portion of the burner case and conceals the burner operating mechanism therein, an attractive and pleasing effect is produced.

I claim as my invention:

1. A cooking stove comprising, in combination, a burner compartment having a cooking top and end and back walls, a member extending transversely across the front of said compartment below the cooking top, burners disposed within said compartment beneath said cooking top, and a burner skirt extending transversely across the lower portion of the open front of said compartment, the lower side of said skirt being constructed to embrace the front edge of said member.

2. A cooking stove having, in combination with a burner compartment having an open front, a burner skirt extending transversely across the open front of said compartment, said skirt comprising an upper portion mounted within said compartment in spaced relation to the front thereof, and a lower portion extending from said upper portion forwardly of the compartment to the front face thereof to designate the bottom of said compartment, the front edge of said lower portion being bent to form a channel.

3. An oil cook stove having, in combination with stove burners and operating means therefor including handles for manual operation of the burners extending toward the front of the stove, a burner skirt disposed vertically to extend transversely across the stove intermediate the operating mechanism and the front of the stove, said skirt being apertured to permit said handles to extend therethrough, and a shelf member rigid with said burner skirt and extending forwardly therefrom to the front of the stove in underlying relation to said operating handles.

4. A burner skirt for a cooking stove of the character described comprising, in combination, a member adapted to fit across the front of the stove having an upper portion arranged for vertical disposition in said stove, a lower portion extending substantially at right angles to said upper portion, and a flange formed on the free edge of said lower portion to extend substantially parallel to said upper portion in the opposite direction from said lower portion.

5. In combination with a cooking stove of the character described, a burner skirt comprising a member formed of sheet metal having an upper portion adapted to fit across and within the front of the stove, a lower portion turned forwardly of said upper portion to form a shelf in front of said upper por-

tion, securing flanges at each end of said upper and lower portions, and a channel formed to receive a stove part by bending the front edge of the lower portion downwardly and then rearwardly.

5 6. A cook stove having, in combination with stove burners and operating mechanism therefor having handles extending towards the front of the stove for manually operating said burners, a burner skirt disposed vertically to extend transversely across the stove forwardly of the operating mechanism, said skirt being apertured to permit said handles to extend therethrough, and a shelf member 10 extending forwardly from said burner skirt in underlying relation to said operating handles.

15 In testimony whereof, I have hereunto affixed my signature.

20 WILLIAM L. COOPER.
